UNITED STATES PATENT OFFICE.

MILTON DENNEY, OF TIPTON, MICHIGAN.

STRAINER AND DIRT COLLECTOR.

Application filed December 30, 1926. Serial No. 158,010.

This invention relates to a strainer and dirt collector and it is an object of the invention to provide a device of this kind wherein air or other fluids has effectively separated therefrom dirt or other foreign matter which may be carried thereby.

It is also an object of the invention to provide a device of this kind embodying a member through which fluid to be treated passes together with a strainer interposed in the line of travel of the fluid through the member, a part of such member constituting a collecting cup for dirt or other foreign matter.

15 The invention consists in the details of construction and in the combination and arrangement of the several parts of my improved strainer and dirt collector whereby certain important advantages are attained and the device rendered simpler, less expensive and otherwise more convenient and advantageous for use, as will be hereinafter more fully set forth.

20 The novel features of my invention will hereinafter be definitely claimed.

In order that my invention may be the better understood I will now proceed to describe the same with reference to the accompanying drawing, wherein:—

25 Figure 1 is a view in side elevation of a strainer and dirt collector constructed in accordance with an embodiment of my invention;

Figure 2 is a view in top plan of the device as illustrated in Figure 1;

30 Figure 3 is a sectional view taken substantially on the line 3—3 of Figure 2;

Figure 4 is a sectional view taken substantially on the line 4—4 of Figure 1;

35 Figure 5 is a sectional view taken substantially on the line 5—5 of Figure 3.

As disclosed in the accompanying drawing, B denotes a body, preferably cast, and substantially T-shaped in elevation. This body B comprises two bores or passageways 1 each leading from an end of the head portion 2 of the body and terminating at the lower end of the stem portion 3. Each of the bores or passageways 1 at its upper portion, or that extremity at an end of the head 2, has its walls internally threaded, as at 4, whereby the device may be readily interposed within a desired line. It is to be understood, however, that the body B may 50 be coupled within a line in any other man-

ner preferred. I find it of advantage to provide the head portion 2 of the body B with an arrow 5 or other indication so that it may be readily determined in which direction fluid is passing through the device 55 when in applied or working position.

The lower or free end portion of the stem 3 of the body B is provided with a circular flange 6 through which are disposed the holding bolts 7. These bolts 7 are also directed through the outstanding flange 8 defining the upper end portion of the cup or bowl member C whereby the members B and C are effectively maintained in applied position. Interposed between the members B 70 and C and their flanges 6 and 8 is a gasket 9 of desired material whereby leakage between the assembled members is prevented. This gasket 9 may be made of rubber, copper, lead, or any material that will assure an air 75 or watertight joint.

The upper end of the cup or bowl member C is partially closed by a plate 10 integrally formed with the member and which provides a relatively large opening 11 with which the 80 inlet bore or passageway 1 communicates. Carried by the side wall of the member C and extending inwardly and downwardly thereof is a plate 12, said plate extending entirely across the adjacent end of the inlet bore or passageway 1 and terminating at a point inward of the plate 10 hereinbefore referred to. The plate 10 is provided with an opening 14 which registers with the outlet bore or passageway 1 of the body B. 85 Extending within the member C through the opening 14 is a straining element 15. This element 15 is what might be termed funnel-shaped and has its open end upwardly disposed. This open end is defined by an outstanding flange 16 which is received within a rabbet 17 provided in the inner end of the outlet bore or passageway 1 whereby the straining element is effectively maintained in desired position when the members B and C 100 are assembled.

The bottom or outer end 18 of the member C is provided, preferably at its axial center, with an opening 19 normally closed by the plug 20.

105 As the fluid passes into the member C through the intake bore or passageway 1 the flow is deflected by the plate 12 resulting in a portion of the dirt or foreign matter within the fluid being thrown to the bottom of 110

the member C. The fluid as it passes out through the outlet passageway or bore 1 first passes through the element 15, said element 15 being of a character to substantially entirely remove from the fluid all dirt or foreign matter.

This strainer 15 will be made of such material as its particular use may prefer. When my improved device is employed in connection with the air line of an air brake equipment a screen of desired mesh suffices although, on the other hand, if my improved device is to be used for separating dirt or foreign matter, such as water, from gasoline the straining element is of chamois. However, as I do not wish to limit myself to the particular or specific type of straining element it is not believed a further detailed disclosure is necessary.

20 While I have found my improved strainer and dirt collector can be employed to advantage in connection with water, gas, gasoline, etc., I have particularly used the same in connection with an air line of an air 25 brake equipment. When so used I found that effective operation or functioning of the triple valves is assured resulting in a quicker starting of the train with less chance of the train breaking in two and substantially 30 eliminating the liability of flat wheels, hot journals, damaged and pulled out draft rigging together with a material saving in fuel. These advantages can be directly attributed to the keeping of dirt and foreign 35 matter from the triple valves.

By removing the plug 20, which can be very readily done, it is possible to determine in cold weather if the member C is clogged with ice and also provides a pronounced saving in time and labor when inspecting a frozen brake system. It is to be understood that at all times the removal of the plug 20 facilitates the cleaning out of the member C.

40 It is also to be particularly noted that my improved device is one wherein the strainer and the dirt collector are combined in a single unit, thus avoiding two pipe connections required on present air brake 50 equipment. This materially reduces the cost of maintenance and at the same time reduces the risk of breakage.

From the foregoing description it is thought to be obvious that a strainer and 55 dirt collector constructed in accordance with my invention is particularly well adapted for use by reason of the convenience and facility with which it may be assembled and operated, and it will also be 60 obvious that my invention is susceptible of some change and modification without departing from the principles and spirit thereof and for this reason I do not wish to be understood as limiting myself to the precise 65 arrangement and formation of the

several parts herein shown in carrying out my invention in practice except as herein-after claimed.

I claim:—

1. A combined strainer and dirt collector 70 comprising a body member having disposed therethrough an inlet bore and an outlet bore, a cup member, means for securing the body and cup member one to the other, the bores of the body member being in communication with the interior of the cup member, a plate carried by a wall of the cup member and extending inwardly thereof and across the point of communication between the cup member and the inlet bore, 80 a plate partially closing the end of the cup member immediately adjacent to the body member, said last named plate having an opening communicating with the outlet bore of the body member, and a straining 85 element extending within the cup member through the opening in the last plate.

2. A combined strainer and dirt collector comprising a body member having disposed therethrough an inlet bore and an outlet 90 bore, a cup member, means for securing the body and cup member one to the other, the bores of the body member being in communication with the interior of the cup member, a plate carried by a wall of the cup 95 member and extending inwardly thereof and across the point of communication between the cup member and the inlet bore, a plate partially closing the end of the cup member immediately adjacent to the body 100 member, said last named plate having an opening communicating with the outlet bore of the body member, and a funnel like straining element extending within the cup member through the opening in the last 105 plate.

3. A combined strainer and dirt collector comprising a body member having disposed therethrough an inlet bore and an outlet bore, a cup member, means for securing the body and cup member one to the other, the bores of the body member being in communication with the interior of the cup member, a plate carried by a wall of the cup member and extending inwardly thereof 110 and across the point of communication between the cup member and the inlet bore, a plate partially closing the end of the cup member immediately adjacent to the body member, said last named plate having an opening communicating with the outlet bore of the body member, and a straining element held to the body by the last named plate and intersecting the flow through the 115 opening in the last named plate.

4. A combined strainer and dirt collector comprising a body member having disposed therethrough an inlet bore and an outlet bore, a cup member, means for securing the body and cup member one to the other, the 120 125

bores of the body member being in communication with the interior of the cup member, a plate carried by a wall of the cup member and extending inwardly thereof and across the point of communication between the cup member and the inlet bore, a plate partially closing the end of the cup member immediately adjacent to the body

member, said last named plate having an opening communicating with the outlet bore 10 of the body member, and a straining element intersecting the flow through the outlet bore of the body member.

In testimony whereof I hereunto affix my signature.

MILO DENNEY.
